DESIGN FOR A TIE RACK

Herman Martin Canner, Detroit, Mich.

Application April 11, 1947, Serial No. 138,309

Term of patent 3½ years

(Cl. D33—8)

To all whom it may concern:

Be it known that I, Herman M. Canner, a citizen of the United States, residing at Detroit, in the county of Wayne and State of Michigan, have invented a new, original, and ornamental Design for a Tie Rack, of which the following is a specification, reference being had to the accompanying drawing, forming a part thereof, in which:

Fig. 1 is a view in perspective of a tie rack embodying the invention; and

Fig. 2 is a fragmentary side elevational view showing the tie rack with its drawer out and its tie supporting arms extended; and

Fig. 3 is a top plan view.

I claim:
The ornamental design for a tie rack, substantially as shown.

HERMAN M. CANNER.
